TUBE BEADING AND FLARING MACHINE

Emmett C. Hartley and Henry E. Hull, Cleveland,
Ohio, assignors to The Parker Appliance Com-
pany, Cleveland, Ohio, a corporation of Ohio

Application July 22, 1943, Serial No. 495,740

13 Claims. (Cl. 153—2)

1

The invention relates generally to the art of metal bending and primarily seeks to provide a novel, simple and compact machine capable of efficiently beading or flaring tubes with equal facility.

In its more detailed nature the invention resides in providing a novel machine structure of the character stated in which is included a rotor, a shiftably mounted bending tool supporting arm rotatable with the rotor, tube holding means, means for bringing about relative movement between the holding means and the arm to present the tool in the tube, means normally holding the tool approximately centered with respect to the tube, means for rotating the rotor, and means for shifting the arm to force the tool outwardly against the tube while the rotor is turning for working the tube.

An object of the invention is to provide a machine of the character stated in which the shiftable arm is equipped with a novel mounting in which selected tools of a selective multiple set of beading and flaring tools are readily detachably mounted.

Another object of the invention is to provide a machine of the character stated in which the tube holding means includes a die block equipment which is reversibly mounted and has a first selective form surface at one end against which tube wall portions are forced for beading purposes, and a second selective form surface at its other end against which tube wall portions are forced for flaring purposes.

Another object of the invention is to provide a machine of the character stated in which the die block equipment is composed of half dies each carried by a shiftable arm, and in which there is included means for separating the arms by movement of separation imparted to both arms.

Another object of the invention is to provide a machine of the character stated in which the die block halves have half circular rubber gripper sleeves projecting a distance inwardly from the tube opposing faces of the blocks thereby to tightly grip a tube between them while permitting the block halves to directly contact one with the other.

Another object of the invention is to provide a machine of the character stated in which there is included a rotor housing on which the tube holding means is mounted, means for shifting the housing longitudinally with relation to the rotor and the tool carrying arm for properly positioning the selected tool relative to the die block equipment, and means for securing the housing in adjusted positions.

Another object of the invention is to provide a machine of the character stated in which the arm shifting means comprises a cam movable longitudinally with respect to the rotor, a lever

2

equipment for moving the cam, and adjustable means for limiting movement of the lever equipment.

With the above and other objects in view that will hereinafter appear, the nature of the invention will be more fully understood by following the detailed description, the claims and the several views illustrated in the accompanying drawings.

In the drawings:

Figure 1 is a vertical central longitudinal section of a machine embodying the invention, the section being taken on the line 1—1 on Figure 4 and parts being shown in elevation.

Figure 2 is a fragmentary plan view of a portion of the removable base cover.

Figure 3 is a horizontal sectional view taken on the line 3—3 on Figure 1, through the axis of the rotor.

Figure 4 is a right hand end elevation.

Figure 5 is a fragmentary end elevation illustrating the rotor and the tool carrying arm mounted thereon.

Figure 6 is a fragmentary vertical cross section illustrating the collar shifting arms.

Figure 7 is a fragmentary end elevation illustrating the die carrying arms swung to the open or separated position.

Figure 8 is a fragmentary vertical longitudinal section illustrating a flaring tool as supported on the tool carrying arm and rotor and engaged in the end of a clamped tube preparatory to a flaring operation.

Figure 9 is a view similar to Figure 5, the tool carrying lever being shown as moved against the limiting stop which limits the degree of off-center position of the tool.

Figure 10 is a fragmentary cross sectional view taken on the line 10—10 on Figure 9.

40 In the improved machine structure herein disclosed as an example of embodiment of the invention there is included a base 5 having an upstanding bearing 6 in which a long bearing sleeve 7 is horizontally disposed in the manner clearly illustrated in Figures 1 and 3 of the drawings.

The bearing sleeve 7 is secured in the supporting bearing 6 by a dowel 8 which is held in place by a cross bridge 9 forming a part of a base cover or protective shell 10 which is removably secured as at 11 in the upstanding bearing 6 in the manner best illustrated in Figures 1 and 2 of the drawings.

55 The base 5 is provided with a central longitudinal depression 12 which serves to provide the base with longitudinally extending shelf portions whereon are provided supporting guideways 14. The guideways 14 serve as slide supports for the mounting bosses 15 which extend laterally from the housing body 16. The bosses 15 are provided with vertically disposed longitudinal slots 17, and

clamping screws 18 extend downwardly through said slots and into receiving taps in the guideways 14 for securely clamping the housing in positions of longitudinal adjustment on said guideways. The structure of the housing 16, 18 will be best understood by reference to Figures 1, 3 and 4 of the drawings from which it will be observed that a rack 19 is secured to the bottom of the housing and is engaged by an adjuster pinion 20 fixed on one end of an adjuster shaft 21 which is transversely disposed and rotatably mounted in a frame bearing 22. Through the medium of the knurled turning head 23 fixed to the outer end of the adjuster shaft 21 said shaft may be rotated for imparting longitudinal movement of adjustment to the housing.

A shaft 24 is rotatably mounted in the bearing sleeve 7 and extends at both ends from said sleeve. At its front end the shaft is provided with an abutment head 25, and a cylindrical rotor 26 is keyed on the shaft as shown at 27 and between the abutment head 25 and the adjacent end of the long sleeve bearing 7. It will be observed by reference to Figures 1 and 3 of the drawings that the front end of the sleeve 7 extends a distance into the rear end of the rotor 26 as at 28 and cooperates with the abutment head 25 in holding the rotor against longitudinal movement relative to the shaft 24.

The other or rear end of the shaft 24 is coupled as at 29 with a driving motor 30 mounted on the base in the manner clearly illustrated in Figure 1.

The rotor 26 is freely rotatable within a cylindrical bore 31 in the housing body 16, as will be apparent by reference to Figures 1 and 3 of the drawings.

A grooved shifter collar 32 is longitudinally-slidably mounted on the sleeve 7 between the upstanding bearing 8 and the rear end of the rotor 26. A pair of shifter rollers 33 extend into the collar groove in the manner clearly illustrated in Figures 1, 3 and 6, and each said roller is carried at the upper end of an arm 34 which is secured to a cross shaft 35 rockably mounted as at 36 on the base 5. An actuator lever 37 is secured to the outer end of the shaft 35, and said lever is engageable with an adjustable stop screw equipment 38 which is vertically-adjustably mounted in a threaded bore provided in the base boss 39. The position of the stop screw 38 determines the degree to which the lever can be depressed for the purpose of shifting the collar 32 to the right as viewed in Figures 1 and 3, and adjustments of the stop screw 38 can be secured by the jam nut forming a part of the stop screw equipment. The collar 32 is normally held in the retracted position illustrated in Figures 1 and 3 by the spring means 40.

A mounting lug 41 extends forwardly from the central lower portion of the housing body 16, and two freely disposed holder arms 42 are pivoted at their lower ends as at 43 on said lug in the manner clearly illustrated in Figures 1 and 4 of the drawings. Each arm has a recess 44 in the inner face thereof in which a half circular die block 45 is removably secured by screw means 46. Arcuate angle plates 47 also are removably secured as at 48 to the front faces of the arms in position for overlying the ends of the mounted die blocks so as to take up end thrust on said blocks. The die blocks 45 are reversibly mounted, and each is provided with a flare portion 49 at one end and a beading groove 50 at its inner face adjacent the opposite end. The respective

positions of the die blocks are shown in Figures 3 and 8, respectively. It will also be observed that each die block 45 is provided with a recess between the flared and beaded ends thereof in which is mounted a rubber half sleeve 51, and each said sleeve extends a distance inwardly beyond the inner face of the respective die block so as to tightly grip a tube clamped between the die blocks and yet permit the opposed edge portions of the half circular die blocks 45 to contact in the manner clearly illustrated in Figure 4 and present a continuous flaring or beading function backing surface.

Each of the upstanding arms 42 is bifurcated at its upper end, and one has a link 52 pivoted thereto as at 53, said link having two downwardly turned end portions, and the other has a link 54 pivoted thereto as at 55, said last named link 54 having the end thereof which is pivoted to the arm upwardly turned and its other end straight. The inner ends of the links 52 and 54 are respectively pivoted as at 56 at like distances from the axis of and between the longitudinally spaced heads 57 mounted on a shaft 58 which is rockably mounted in a longitudinal bearing 59 provided therefor on the housing body 16 in the manner clearly illustrated in Figures 1 and 4. An irregularly shaped connector piece 60 is interposed between the heads 57, and said heads 30 connect with or are extended in the form of a toggle actuator handle 61.

It will be apparent by reference to Figures 1, 4 and 7 of the drawings that when the handle 61 is disposed in the position illustrated in Figure 35 the links 52 and 54 will be drawn together to securely toggle lock the arms 42 together with the rubber inserts 51 securely clamping a tube therebetween and the half circular die blocks 45 contacting in the manner hereinbefore referred to, one link 54 underlying the irregular connector piece 60 and the other link 52 overlying the same. When the lever is swung from the position illustrated in Figure 4 to the position illustrated in Figure 7 the links 52 and 54 will be forced apart and movement of separation will be imparted to both arms 42 for separating them in the manner clearly illustrated in Figure 7 and providing for removal of the worked tube with great facility.

50 A hollow, U-shaped housing 62 is secured as at 63 in a receiving recess 64 provided in the front end of the rotor 26. Within the housing 62 a tool carrying lever 65 is swingably mounted on a pivot pin 66 secured to the housing 62 and extending into a socket 67 provided therefor in the rotor 26. See Figures 1, 3 and 5. The lever 65 is provided with a center boss or bearing 68 having an axial bore equipped with needle bearings 69 and closed at its rear end by a closure plate 70. The lever bore is designed to removably receive the shank 71 of a tube working tool having a beading head 72 as in Figures 1, 3 and 4, or a flaring head 73 as in Figure 8.

Each of the selective tool shanks 71 is provided 65 with an annular keeper groove 74 adapted to receive a retainer detent 75 which is guided in a bore 76 formed in the lever boss or bearing 68, a compression spring 77 serving the two-fold purpose of yieldably urging the detent into tool 70 securing engagement in the shank groove 74 and for holding the arm in its normal or inactive position illustrated in Figures 1 and 3, in which position the selected tool will be disposed in coaxial relation with the shaft 24.

The lever 65 is provided with an angularly dis-

posed extension leg 18 at the outer end of which is mounted a roller 79 which normally engages a cam face 80 on a cam plunger 81 in the manner illustrated in Figure 3 for cooperating with the spring 77 in normally holding the tool centered as hereinbefore described. The plunger projects forwardly from the shifter collar 32 and through a bore 82 provided therefor in the rotor 26. The collar 32 also is provided with a guide pin 83 which is slidably guided in a bore 84 in said rotor. It will be apparent that whenever the plunger 81 is moved forwardly by forward shifting of the collar 32, engagement of the cam face 80 with the roller 79 will serve to displace the lever 65 and cause the beading head 72 or the flaring head 73 to move off center and work the clamped tube either into the beading groove 50 or against the flare 49 of the die block equipment 45, depending upon the position of said equipment and the selection of tool. The lever 65 is provided with another extension 85 which is engageable with a limiting stop 86 provided in the housing 62 for the purpose of limiting the degree of off center movement that can be imparted to the beading or flaring tool.

In operating the machine for effecting a beading operation, the housing body 16 is first adjusted with respect to the base 5 and secured in proper position on said base, by manipulation of the clamping screws 18 so that the beading head 72 is disposed directly opposite the groove 50 in the die block equipment. The tube T which is to be beaded is securely clamped between the die block halves by moving the arms 42 from the position illustrated in Figure 7 to the position illustrated in Figure 4, with the end of the tube abutting the front face of the lever portion 78. This serves to properly locate the bead with respect to the end of the tube. As has been described previously, the rotor 26 rotates with the shaft 24 and the tool carrying arm 65, 78, 85 is carried by said rotor. It has been described also that the beading tool 71, 72 normally is disposed with its center aligned with the axis of the shaft and rotor.

When it is desired to bead the tube, the actuating lever 37 is depressed and the arms 34 are moved to slide the collar 32 forwardly over the bearing sleeve 7 and toward the rotor 26. The camming surface 80 on the pin 81 causes the roller 79 to move inwardly and force the beading head 72 against the internal surface of the tube T so as to bend the tube wall into the beading groove 50 and form the desired bead. When the beading operation has been completed the actuating lever 37 is released and the collar 32 is returned to the normal position illustrated in Figures 1 and 3 by action of the springs 40. This movement of the collar 32 retracts the cam surface 80, and the tool carrying arm 65 is returned to its normal, tool centered position by action of the spring 77. By now swinging the toggle lever 61 from the position illustrated in Figure 4 to the position illustrated in Figure 7, movement of separation will be imparted to both arms 42 to move them to the position illustrated in Figure 7. Thus the beaded tube can be withdrawn with great facility.

When it is desired to flare the end of the tube, a flaring tool 73 is substituted for the beading tool 72, and the die block equipment 45 is reversed so as to present the flare surface 49 thereof in opposition to the tool instead of the beading groove 50. After the housing body 16 has been adjusted in the manner hereinbefore de-

scribed to place the flaring tool in the manner illustrated in Figure 8, the actuating lever 37 is manipulated in the manner above described to move the flaring head 73 off center and cause this rotating element to flare the tube against the flare surface 49 of the die block equipment.

It is of course to be understood that the details of structure and the arrangement of parts may be variously changed and modified without departing from the spirit and scope of the invention.

We claim:

1. In a machine of the character described, a rotor, a tube bending tool supporting arm swingably mounted on said rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, means movable with the rotor and engageable with the arm for shifting the arm to force the tool outwardly against the tube while the rotor is turning for working said tube, a U-shaped housing mounted on said rotor and partly housing said swingably mounted arm, and means on said U-shaped housing engageable by said arm for limiting swinging movement of said swingably mounted arm.
2. In a machine of the character described, a rotor, a tool supporting arm shiftably mounted on said rotor and having a tool shank receiving socket therein, a tool having a shank mountable in said arm socket and having a recess therein, a retainer detent mounted on the rotor and engageable in the tool shank recess, and a single spring means constantly tending to hold the arm in a predetermined position on said rotor and yieldably holding said detent in said shank recess.
3. In a machine of the character described, a rotor, a shiftably mounted tube bending tool supporting arm rotatable with the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, and means for shifting the arm to force the tool outwardly against the tube while the rotor is turning for working said tube, said arm being equipped with a receiving socket for removably mounting a selected one of different types of tube bending tools such as a tube beader or flarer, and said tube holding means including a die block equipment for embracing the tube and having a flare form surface at one end and a bead form surface at its other end, said die block equipment being reversibly mounted so that one or the other of said ends can be presented for cooperation with the selected tool.

4. In a machine of the character described, a rotor, a shiftably mounted tube bending tool supporting arm rotatable with the rotor, tube holding means, means supporting said tube holding means adjacent said arm, means for bringing about relative movement between the holding means and the arm to present the tool in a tube held by said tube holding means, means engaging said arm in a manner for normally holding the

tool supported thereon in a position for entering the tube, means for rotating the rotor, means for shifting the arm to force the tool outwardly against the tube while the rotor is turning for working said tube, a base, a housing shiftably mounted on the base and surrounding the rotor and providing a support for the tube holding means and in such position that a tube held by said holding means may be accurately placed by end abutment against the tool supporting arm rotatable with said rotor, and means for holding the rotor against longitudinal movement relative to said base, said means for bringing about relative movement comprising a rack on said housing, a shaft, a bearing for said shaft fixed on the base, and a pinion on said shaft and meshing with said rack, and means for securing the housing in positions of adjustment on said base.

5. In a machine of the character described, a rotor, a tube bending tool supporting arm rotatable with the rotor and swingably mounted for swinging movement in a plane perpendicular to the axis of the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, means for swinging the arm to force the tool outwardly against the tube while the rotor is turning for working said tube, a pair of cooperatively opposing shiftable carrier arms, said holding means comprising a pair of matching half dies each carried by one of said carrier arm, and means for separating the half die carrying arms by movement of separation imparted to both said carrying arms.

6. In a machine of the character described, a rotor, a tube bending tool supporting arm rotatable with the rotor and swingably mounted for swinging movement in a plane perpendicular to the axis of the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, and means for swinging the arm to force the tool outwardly against the tube while the rotor is turning for working said tube, said holding means comprising a pair of matching metallic half dies each having a half circular rubber gripper sleeve projecting a limited distance inwardly from the tube opposing face of the die, thereby permitting the half dies to firmly grip a tube between them with deformation of the rubber gripper sleeve permitting the block halves to directly contact one with the other and form circular metal die surfaces.

7. In a machine of the character described, a rotor, a shiftably mounted tube bending tool supporting arm rotatable with the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, means for shifting the arm to force the tool outwardly

against the tube while the rotor is turning for working said tube, said arm being equipped with a receiving socket for removably mounting a selected one of different types of tube bending tools such as a tube beader or flarer, and said holding means comprising a pair of matching metallic half dies each having a flare form surface at one end and a bead form surface at its other end, said die block equipment being reversibly mounted so that one or the other of said ends can be presented for cooperation with the selected tool, and each said half die having a half circular rubber gripper sleeve projecting a limited distance inwardly from the tube opposing face of the die between the flare and bead form surfaces thereon, thereby permitting the half dies to firmly grip a tube between them with deformation of the rubber gripper sleeve permitting the block halves to directly contact one with the other and form circular metal die surfaces without break in said flare and bead form continuities.

8. In a machine of the character described, a rotor, a tube bending tool supporting arm rotatable with the rotor and swingably mounted for swinging movement in a plane perpendicular to the axis of the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, means for swinging the arm to force the tool outwardly against the tube while the rotor is turning for working said tube, said arm being equipped with a receiving antifriction bearing for removably and freely rotatably mounting a selected one of different types of tube bending tools such as a tube beader or flarer, and spring detent means for yieldably retaining the selected tool in said bearing.

9. In a machine of the character described, a rotor, a tube bending tool supporting arm rotatable with the rotor and swingably mounted for swinging movement in a plane perpendicular to the axis of the rotor, tube holding means, means supporting said tube holding means adjacent said arm, means for bringing about relative movement between the holding means and the arm to present the tool in a tube held by said tube holding means, means engaging said arm in a manner for normally holding the tool supported thereon in a position for entering the tube, means for rotating the rotor, and means for swinging the arm to force the tool outwardly against the tube while the rotor is turning for working said tube, said holding means including matching half dies, two shiftable arms each carrying a half die and both pivotally mounted on a single pivot, and lever and toggle link means movable in one direction for separating the half die carrying arms by movement of separation imparted to both said carrying arms and movable in the opposite direction for bringing the half dies together and locking them together.

10. In a tube beading machine, a rotor, a swingably mounted tube beading tool supporting arm rotatable with the rotor, tube holding means having a beading clearance therein, means supporting said tube holding means adjacent said arm and in position so that a tube inserted in the holding means is directly engageable with said swingably mounted arm as a stop definitely placing the tool a predetermined distance in the tube

for beading said tube a predetermined distance from the arm engaging end thereof, means normally holding the arm with the tool approximately centered on the tube and rotor axes, means for rotating the rotor, and means for swinging the arm to force the tool outwardly against the tube opposite said beading clearance while the rotor is turning for beading said tube.

11. In a tube beading machine, a rotor, a shiftably mounted tube beading tool supporting arm rotatable with the rotor, tube holding means having a beading clearance therein, means supporting said tube holding means adjacent said arm and in position so that a tube inserted in the holding means is engageable with said arm as a stop definitely placing the tool a predetermined distance in the tube for beading said tube a predetermined distance from the arm engaging end thereof, means normally holding the arm with the tool approximately centered on the tube and rotor axes, means for rotating the rotor, and means for shifting the arm to force the tool outwardly against the tube opposite said beading clearance while the rotor is turning for beading said tube, said arm being swingably mounted on the rotor and having a roller directly mounted thereon in spaced relation to the swing center of the arm, and said shifting means including a plunger longitudinally slidable in a bore in the rotor paralleling the rotor axis and having a cam surface at an end thereof engaging the arm roller, and means manually operable for moving said plunger.

12. In a tube beading machine, a rotor, a shiftably mounted tube beading tool supported arm rotatable with the rotor, tube holding means having a beading clearance therein, means supporting said tube holding means adjacent said arm and in position so that a tube inserted in the holding means is engageable with said arm as a stop definitely placing the tool a predetermined distance in the tube for beading said tube a predetermined distance from the arm engaging end thereof, means normally holding the arm with the tool approximately centered on the tube and rotor axes, means for rotating the rotor, means for shifting the arm to force the tool outwardly against the tube opposite said beading clearance while the rotor is turning for beading said tube, said arm being swingably mounted on the rotor and having a roller directly mounted thereon in spaced relation to the swing center of the arm, said shifting means including a plunger longitudinally slidable in a bore in the rotor paralleling the rotor axis and having a cam surface at an end thereof engaging the arm roller, a collar slidable along the axis of the rotor and

attached to said plunger, means including a manually swingable lever for shifting the collar, and adjustable stop means for limiting swinging of the lever in a direction for forcing the tool against the tube.

13. In a tube beading machine, a rotor, a shiftably mounted tube beading tool supporting arm rotatable with the rotor, tube holding means having a beading clearance therein, means supporting said tube holding means adjacent said arm and in position so that a tube inserted in the holding means is engageable with said arm as a stop definitely placing the tool a predetermined distance in the tube for beading said tube a predetermined distance from the arm engaging end thereof, means normally holding the arm with the tool approximately centered on the tube and rotor axes, means for rotating the rotor, means for shifting the arm to force the tool outwardly against the tube opposite said beading clearance while the rotor is turning for beading said tube, means for adjusting the spaced relation of said arm and said holding means for varying said predetermined distance of the tube beading, and means for replaceably mounting beading tools on said arm.
